ATTORNEYS.

UNITED STATES PATENT OFFICE.

PERCY WILLIAM HUSKISSON, OF POOLE, ENGLAND.

CARBURETER.

1,157,541.

Specification of Letters Patent.

Patented Oct. 19, 1915.

Application filed October 9, 1914. Serial No. 865,881.

To all whom it may concern:

Be it known that I, PERCY WILLIAM HUSKISSON, a subject of the King of Great Britain, and resident of Poole, in the county of Dorset, England, have invented certain new and useful Improvements in Spray-Carbureters for Use on Internal-Combustion Engines, of which the following is a specification.

10 This invention relates to spray carbureters for use on internal combustion engines and has for its object to provide a simple type of carbureter having a spring-loaded valve controlling the passage of air over the jet nozzle.

In the accompanying drawings, Figure 1 is a central vertical section showing a carbureter constructed in accordance with this invention, the float chamber being omitted.

20 Fig. 2 is a cross section on the line 2—2 of part of Fig. 1 looking toward the left. Fig. 3 is a plan view of the valve and Fig. 4 is a part sectional view of a modification.

Like letters indicate like parts throughout the drawings.

In this construction the spraying chamber A is roughly tubular and is horizontally arranged, although it may of course be vertical. At one end of the spraying chamber 30 is provided an attachment B to enable it to be coupled to the inlet pipe, while the other end is closed. About midway in the length of the spraying chamber a fuel nozzle D is arranged, this being screwed into the top 35 of a vertical tube E which is in communication with a float feed mechanism of the ordinary type (not shown). Preferably the fuel nozzle projects only slightly above the bottom of the spraying chamber, as shown.

40 The air inlet F is in the side of the spraying chamber A so that, as shown by the arrow in Fig. 1, the air inlet is at right angles to the axis of the spraying chamber. This air inlet F is provided with a disk 45 valve G which is pressed downward by a spring G² and is adapted to slide on a rod G³ while the guide rod G⁴ prevents its rotation. In the construction shown in Fig. 4 the valve G is pivoted at G⁶ and the leaf spring H presses upon it. One end of this L shaped spring H presses against an ad-

justable set screw H² by the movement of which the pressure on the hinged valve can be varied. In the construction shown in Fig. 1 the spring G² abuts against a screwed stem G¹ by the adjustment of which the pressure on the valve can be varied. The valve rests upon a buffer spring G⁸.

In the valve is formed a channel J which extends from the hinge to that side of the disk adjacent to the fuel nozzle, and in cross section it may be of the shape of the fuel nozzle, see Fig. 2, the idea being to concentrate the air, at low engine speeds, as close to the nozzle as possible.

The outlet from the nozzle may be adjustable by means of a dipping-needle K. Preferably the needle terminates in a ball L at the upper end which engages a housing suspended from an operating wire or rod M. Thus the needle is perfectly free and cannot bind or wear in the fuel nozzle. On the outlet side of the fuel nozzle is the throttle slide N, which may be rectangular or circular.

It will be seen that by this invention a very simple form of carbureter is provided in which, at slow speeds, all the air is concentrated near the jet nozzle so that efficient slow running and acceleration can be obtained accompanied by economy of fuel and simplicity of operation.

What I claim as my invention and desire to secure by Letters Patent is:—

In combination, a spraying chamber, a jet nozzle projecting through one wall of said chamber, a closed end to said chamber, an air inlet adjacent to said jet nozzle, a spring-loaded valve controlling said inlet, and a groove or channel in said valve varying in depth and adapted to direct the entering air over said jet nozzle at an acute angle to the horizontal plane of the spraying chamber, substantially as set forth.

In testimony whereof I have signed my name to this specification in the presence of two subscribing witnesses.

PERCY WILLIAM HUSKISSON.
